HENRY ASBURY TRUITT, OF PHILADELPHIA, PENNSYLVANIA, ASSIGNOR
TO THOMAS DOLAN, OF SAME PLACE.

Design No. 4,663, dated February 14, 1871.

DESIGN FOR TASSELED FRINGE.

The Schedule referred to in these Letters Patent and making part of the same.

I, HENRY ASBURY TRUITT, of Philadelphia, county of Philadelphia, State of Pennsylvania, have invented or produced a Design for a Tasseled Fringe, of which the following is a specification.

The figure in the accompanying drawings represents a strip of the tasseled fringe made in accordance with my design, the principal features of which are the figures A A and tassels B B.

The figures A adjoin each other, as shown, and are continued throughout the strip; and each figure consists of a transverse double loop, *a*, and four inclined loops *b*, the inclined loops of one figure forming continuations of those of the adjoining figure, and the loops being locked to the fabric at the points where the inclined loops of one figure meet those of the other, by the same threads which connect to the tassel-

threads to the fabric, the said threads, as well as the loops of the figures A being otherwise locked to the fabric, as shown.

Irrespective of the colors employed,

I claim—

The design for a tasseled fringe or border, substantially as described and illustrated in and by the accompanying drawings.

In testimony whereof I have signed my name to this specification in the presence of two subscribing witnesses.

H. A. TRUITT.
